UNITED STATES PATENT OFFICE.

GEORGE POTSTADA, OF OAKLAND, CALIFORNIA.

HINGED CLAMP.

1,360,989.

Specification of Letters Patent. Patented Nov. 30, 1920.

Application filed October 4, 1919. Serial No. 328,473.

To all whom it may concern:

Be it known that I, GEORGE POTSTADA, citizen of the United States, residing at Oakland, in the county of Alameda, State of California, have invented a new and useful Hinged Clamp, of which the following is a specification in such full and clear terms as will enable those skilled in the art to construct and use the same.

10 My invention relates to improvements in hinged clamps, and the object of the present invention is to provide a simple clamp that can be applied to a great variety of uses.

15 Another object of the invention is to provide means for holding articles firmly in any convenient position in relation to other articles.

These and other objects of the invention will appear as the description proceeds.

20 An embodiment of the invention is shown in the accompanying drawings in which the same reference numeral is applied to the same portion throughout, but I am aware that there may be modifications thereof.

25 Figure 1 is a side elevation of this clamp as it appears secured to the edge of a table.

Fig. 2 is a sectional view of the clamp looking in the same direction as Fig. 1 and showing it attached to the side of a table.

30 Fig. 3 is a sectional view of the clamp showing it applied to the table and looking at right angles to Figs. 1 and 2.

35 This clamp is shown applied to the base 1 of a lamp socket 2. The base has its edges flanged as indicated at 3 to form a receptacle

therein for the U-shaped clamp rod 4. The rod 4 is pivotally mounted in two lugs 5 and 6 and a spiral spring 7 tends to hold the U-shaped rod tightly against the inside of the base so that whenever the rod is pulled away 40 from the base as indicated in figures of the drawing, it will tend to return to the base with sufficient force to hold the base 1 in any desired position. The lamp 8 is shown in the socket, but it will be clear that the 45 base may be used for other purposes than that of holding a lamp.

What I claim is as follows, but various modifications may be made in the construction shown in the drawings and above particularly described form, within the purview of my invention:

1. A clamp comprising a base having a flange to raise the base from its support, a U-shaped rod having one leg pivotally connected to the base and a spiral spring for holding the rod normally within the plane of the flange, whereby objects connected with the base may be secured to a table or the like. 55

2. A flanged base, a U-shaped rod having one leg pivotally mounted within the base and a spiral spring surrounding said leg of the rod arranged to normally hold the rod against the base within the plane of the flange. 60

65 In testimony whereof I have hereunto set my hand this 29th day of September A. D. 1919.

GEORGE POTSTADA.
